ABSTRACT

A fuel injection device includes means whereby a rotating flow of an air/fuel mixture is sandwiched between rotating internal and external air flows. The components of the device are grouped into separately mounted sub-assemblies which are movable slidably relative to one another.

7 Claims, 4 Drawing Figures

FUEL INJECTION DEVICES

This invention relates to a high-performance fuel injection device designed particularly for aircraft jet propulsion systems and in which an intermediate annular flow containing fuel is sandwiched between internal and external flows of air caused to rotate by means of inner and outer bladed elements which are normally referred to as "swirlers."

According to the invention, this intermediate annular flow comprises a mixture of air and fuel and is itself caused to rotate by a third bladed element, for example a swirler having helical blades and the components of the device are grouped into two sub-assemblies which are movable slidably relative to one another and are fixed separately to different parts of a fixed structure such as the jet engine combustion chamber.

In a fuel injection device in accordance with the invention the shearing effect which the internal and external flows of air exert on the sandwiched intermediate flow of fuel and air can be increased by giving different rotational angular settings to the vanes or blades of the internal and external swirlers, the external blades having preferably a smaller angular setting than the internal blades.

Relative sliding movement between the two sub-assemblies takes place preferably adjacent the swirler which serves to produce rotation of the external flow of air. To this end, a slideable sleeve is located at the inner periphery of the external swirler.

The invention will now be described by way of example with reference to one embodiment of fuel injection device which is illustrated in the accompanying drawings.

In the drawings:

FIGS. 1 and 2 are transverse and longitudinal cross-sectional views showing the elements of the fuel injection device, FIG. 1 being a section along the line I—I of FIG. 2 and the latter being a section along the line II—II of FIG. 1,

FIG. 3 is an exploded schematic view of the device shown in FIGS. 1 and 2, and

FIG. 4 is a longitudinal sectional view of a device according to the invention and its mounting in a jet combustion chamber.

The fuel injection device shown in FIGS. 1 and 2 comprises an outer liner 1 and a concentric inner liner 2 defining between them an annular passage 3 which is traversed, as indicated by the arrows F1, by air caused to rotate by a swirler 4. A shaped central body or bulb 5 defines, together with a concentric liner 6 placed between it and the inner liner 2, a second passage 7 where primary air, flowing in the manner indicated by the arrows F2, is made to rotate by a swirler 8. Fuel reaches the injection device through a nozzle 9 opening into an annular inlet collector 10. The air/fuel mixture flows into the annular space 11 bounded by the liners 2 and 6, between which is arranged a third swirler 12 ensuring rotation of this air/fuel mixture which flows in the manner indicated by the arrows F3.

The components referred to above are shown in the exploded view of FIG. 3 which illustrates, in a different way, a fuel injection device according to the invention. The outer passage 3 is effected between the outer liner 1 and the inner liner 2. These two elements are interconnected by the vanes or blades of the swirler 4. The liner assembly has a cap 13 and at its base it supports a duct 14 for the entry of the air/fuel mixture.

The intermediate passage 11 is defined between the inner liner 2 and the concentric liner 6, which concentric liner 6 is terminated by a conical cap 15. The liner 6 supports the swirler 12, composed of helical blades 16 and a part-annular rib 17 which diverts part of the air/fuel mixture before it reaches the helical blades 16 so as to accelerate rotation of the mixture and improve the degree of mixing of the mixture. The inner passage 7 is defined between the liner 6 and inner bulb 5; the latter carries the vanes or blades of the swirler 8. The whole device is capped by a plate 18 which is of such size as to afford a circular slot 19 between its inner edge and the cap 13.

The fuel is injected at 9 into the inlet duct 14 which is itself fed by air. The air/fuel mixture then reaches the annular collector 10 and separates into two streams, the first of which passes directly between the helical blades 16, and the second of which circulates around the half rib 17 before reaching the helical blades 16.

The air/fuel mixture is ejected through an annular slot 20 provided between the caps 13 and 15. Air caused to rotate by the outer swirler 4 emerges through the annular slot 19, whilst the air caused to rotate by the inner swirler 8 is ejected through a central opening

21.

A fuel injection device as shown in FIGS. 1 and 2 can with advantage be employed in accordance with the particular method of fitting illustrated in FIG. 4. According to this arrangement, the outer liner 1 forms part of an external sub-assembly A and is screwed directly to the base 22 of the combustion chamber. Its rear part comprises a shoulder 23 on which is welded a thermal screen 24, and its front part carries a thread 25. A threaded ring 26 fits on the thread 25 and holds the liner 1 tightly against the base of the chamber 22. This liner 1 likewise supports, on its inner face, the swirler 4 and the inner periphery of the swirler 4 supports a sleeve 27.

Into this outer sub-assembly A is inserted an inner sub-assembly B comprising the liners 2 and 6, the inner swirler 8, the intermediate swirler 12, the central body 5 and the inlet duct 14, within which is located the nozzle 9 fed with fuel along a passage contained within a supporting arm 28. The sub-assembly B integral with the latter can be introduced into the housing 29 through a suitable hole 30 which is closed by a plate 31 forming an integral part of the supporting arm 28 and fixed by screws 32 to the housing 29.

The outer swirler 4, which forms part of the sub-assembly A, is freely movable relative to the sub-assembly B, and this facilitates mounting and maintenance of the device. During operation, the sub-assembly A is heated considerably and expands, whilst the sub-assembly B is cooled by the circulation of the air/fuel mixture. The necessary play is provided by relative sliding movement between the liner 2 and the sleeve 27. When dismounting, it is merely necessary to remove the screws 32 in order to withdraw the inner sub-assembly B through the hole 30.

60 We claim:

1. In a multi-swirler fuel injection device to be fitted in a combustion chamber having separate and distinct wall elements (22,29) and of the kind designed to produce an inner air swirl (F2), an outer annular air swirl (F1) around and radially spaced from said inner air swirl, and an intermediate annular air/fuel swirl (F3) sandwiched between said inner and outer air swirls, in

combination, the improvement comprising an assembly including a first sub-assembly (A) adapted to be secured to one (22) of said wall elements and comprising an air swirler (4), a second sub-assembly (B) adapted to be secured to another one (29) of said wall elements and comprising another air swirler (8), and guide means (27) mechanically associated with said sub-assemblies for telescoping one into the other in mutually fitting and relatively slidable relationship.

2. A device as claimed in claim 1, wherein said first sub-assembly (A) comprises the air swirler (4) of said outer annular air swirl (F1), and said second sub-assembly (B) comprises the air swirler (8) of said inner air swirl (F2) and is telescopingly fitted into said first sub-assembly (A).

3. A device as claimed in claim 2, wherein said second sub-assembly (B) further comprises a third swirler (12) associated with said intermediate annular air/fuel

swirl (F3).

4. A device as claimed in claim 3, wherein said guide means comprises a sleeve (27) located inwardly of the air swirler (4) of said first sub-assembly (A) and outwardly of the third swirler (12) of said second sub-assembly (B).

5. A device as claimed in claim 4, wherein said sleeve (27) is integral with said air swirler (4) of said first sub-assembly (A) and has a slidable fit with said second sub-assembly (B).

6. A device according to claim 1, wherein the blades of the inner and outer swirlers have different angular rotational settings.

7. A device according to claim 6, wherein the angular setting of the outer blades is less than that of the inner blades.
